United States Patent Office.

CHARLES T. MEYER, OF BERGEN, NEW JERSEY, ASSIGNOR TO EDWARD C. SAMPSON, OF THE CITY OF NEW YORK.

Design No. 2,770, dated August 27, 1867.

DESIGN FOR A CARPET OR OIL-CLOTH PATTERN.

The Schedule referred to in these Letters Patent and making part of the same.

TO ALL WHOM IT MAY CONCERN:

Be it known that I, C. T. MEYER, of Bergen, county of Hudson, State of New Jersey, have originated and designed a new Pattern for Floor Oil-Cloths, or other fabrics, of which the following is a full, clear, and exact description, reference being had to the accompanying specimens or drawings, making part of this specification, and marked or designated as Pattern No. 147, which fully represents said design, and is sufficient without further aid to enable any person skilled in the art to repeat it for practical use.

The colors employed for the different portions of this design may be varied to suit the taste of the manufacturer.

What I claim as my invention, and desire to secure by Letters Patent, is—

The design or pattern for floor oil-cloths, carpets, or other fabrics shown and described.
